SOOT BLOWER

Le Roy S. De Mart, Detroit, Mich., assignor to
 Diamond Power Specialty Corporation, Detroit,
 Mich., a corporation of Michigan

Application August 17, 1938, Serial No. 225,425

7 Claims. (Cl. 122—392)

This invention relates to a fluid heater cleaner of the type in which a blower element is arranged to discharge cleaning fluid adjacent the parts of a fluid heater to be cleaned.

It is the primary object of the invention to provide a cleaner of the above described character which has a blower tube and discharge nozzle capable of axial movement from an inoperative or idle position in the wall of the fluid heater to an operating or blowing position in the fluid heater where it may be rotated about its longitudinal axis any desired number of times without further axial movement while automatically discharging the cleaning fluid, and be then withdrawn to its idle position all through a single operating means.

It is a further feature of the invention to provide an improved method of projecting and retracting the blower element.

A third feature of the invention is to provide means for bringing the full cleaning fluid pressure directly to the blower head and controlling the force of the stream of cleaning fluid discharged into the fluid heater by the size of the inlet ports in the element tube.

Numerous other objects and features of the invention will appear as the description proceeds particularly when reference is made to the drawings wherein like reference characters designate the same parts in all views.

Fig. 1 is a longitudinal sectional view of a fluid heater cleaner constructed in accordance with the teachings of my invention, in its retracted position;

Fig. 2 is an enlarged fragmentary view of the fluid heater cleaner shown in Fig. 1 in its extended or projected position;

Fig. 3 is a cross sectional view of the fluid heater cleaner with a portion broken away to disclose the latching mechanism out of engagement with its cooperating groove;

Fig. 4 is a view in perspective of the latch ring;

Fig. 5 is a perspective view of the latch ring mechanism showing the latch in engagement with its cooperating groove;

Fig. 6 is a fragmentary vertical section of another embodiment of my invention; and

Fig. 7 is a perspective view of the latch ring used with the embodiment disclosed in Fig. 6.

In the drawings wherein like reference characters designate corresponding parts in all views the numeral 67 designates a wall of a fluid heater such, for example, as a boiler, there being portions of the fluid heater, such as tubes, or the like, not shown, which are adapted to be cleaned

by the discharge adjacent the same of cleaning fluid as will hereinafter be more fully apparent.

Mounted in an opening 68 in the wall 67 is a wall box 69 in which a blower nozzle 70 is mounted for rotative and longitudinal movement. This blower nozzle 70 may be of any desired construction having one or more apertures 71 through which the cleaning fluid is discharged toward the portion of the surface to be cleaned. The nozzle 70 is fixedly engaged as by set screws 72 to the element tube 73. Enclosing the element tube 73 at the end opposite the nozzle 70 is the spiral casing 74 to which the spiral 75 is intimately secured as by welding. Spaced from the spiral casing 74 only by the bearing plate 76 and gaskets 77 is the cylinder tube 78. These parts are united by the bolts 79 and together with the bracket 94 comprise a casing for the tube 73.

At the end of the cylinder tube 78 adjacent the nozzle 70, with the blower in its rest position as viewed in Fig. 1, is fitted a fluid chest 80. The cylinder tube 78 and fluid chest 80 are joined together by the bolts 81 and studs 82 at the flanged connections 83 and 84. Bearing plate 81 is held to the fluid chest 80 by the studs 83 and bolts 84. Gaskets 88 and the packing 89 are provided to make the bearing connection fluid tight, gasket 88a seals the connection between the fluid chest 80 and the cylinder tube 78.

Mounted for rotation with the operating shaft 90 is the sheave wheel 91. A spacer tube 90a in which the shaft 90 rotates is fitted between bearing 92 and the hub of sheave wheel 91 and serves to limit the lateral travel of the sheave wheel 91. The spacer tube 90 is journaled in the bearings 92 and 93 which are carried respectively by the bracket 94 and supporting arm 95 of the spiral casing 74. A chain guide 96 is suspended from the operating shaft 90 for positioning the actuating chain (not shown).

Rigidly attached to the drive shaft 97 for rotation therewith is a gear wheel 98 positioned to mesh with the teeth of pinion 99 which is driven by the sheave wheel 91 through operating shaft 90. As shown in Figure 1, the drive shaft 97 is journaled in bearing 100 which is carried by the bracket 94. Bolts 101 hold the bracket 94 to the casing 74 in a relation made fluid tight by the gasket 102. A thrust washer 103 is carried by the drive shaft 97 adjacent the bearing 100.

Positioned on the drive shaft 97 for sliding engagement therewith is the drive nut 104 which is provided with a guide pin 105. As will be apparent from Fig. 3, that portion of the drive shaft 97 within the casing 74 on which the drive nut 104

- 104 slides, is square or it may be of any desired shape which will hold the drive nut 104 from rotation with the shaft 97. A roller 106 at the end of guide pin 105 is designed to rotate freely 5 about the longitudinal axis of the guide pin 105 to prevent any possibility of the guide pin binding in the spiral 75. The arrangement is such that as the drive shaft 97 is rotated through the associated mechanism the element tube 73 and 10 the guide pin 105 are likewise rotated and the travel of the pin 105 in the spiral 75 forces the tube 73 outward from the cylinder tube 78 toward its projected position, the drive nut 104 meanwhile sliding on the shaft 97.
- 15 Located within the casing 74 and positioned between the spiral 75 and the bearing plate 76 is the latch ring 107 mounted for free rotation in one direction about the element tube 73. It is important that the inside diameter of the 20 latch ring 107 be enough larger than the outside diameter of the element tube 73 that there will be no friction between them as the element tube 73 revolves.
- 25 To receive the guide pin 105 as it leaves the spiral 75 a notch 108 is cut out of the latch ring 107. The notch 108 is so designed that as the guide pin 105 moves into it the latch ring 107 is made to revolve with the continued movement 30 of the drive shaft 97 in the same direction, but if the direction of rotation of the drive shaft 97 is reversed the pin 105 is guided back into the spiral and continued movement of the drive shaft 97 in this reverse direction results in the blower tube 73 being retracted to its idle position.
- 35 In order to prevent the latch ring 107 from simply revolving in the reverse direction when it is desired to retract the element tube 73 to its idle position a latch 109 is provided in the cylinder 110 which is located in the wall of casing 40 74. A spring 111 held by the threaded plug 112 urges the latch 109 into constant but flexible engagement with the latch ring 107. Cut into the wall of the latch ring 107 is a groove 113 for receiving the latch 109. The groove 113 is cut 45 with one abrupt edge, perpendicular to the periphery of the ring 107, and the other edge sloping gradually to the periphery of the ring 107. Thus when the direction of rotation is the same as that required to project the element tube 73 50 55 the latch 109 will ride on the periphery of the latch ring, snap over the abrupt edge of the groove 113, and slide back to the periphery of the latch ring 107 as often as it is rotated in this direction. Should the latch ring 107 be rotated in the opposite direction, the latch 109 immediately abuts against the perpendicular edge of the groove 113, the ring 107 is locked against further rotation in this direction and the guide pin is free to move into the spiral 75. As shown 60 in Fig. 5 the arrangement of parts must be such that when the latch 109 is in locking engagement with the groove 113 the notch 108 will be so positioned as regards the end of the spiral 75 that the guide pin 105 may pass readily from the one to the other.

It will be readily apparent that inasmuch as the latch ring 107 cannot move laterally when the guide pin 105 is in driving engagement with it, the tube 73 and hence the nozzle 70 rotate without any forward progress or further axial movement. Thus it will be seen that the blowing operation is confined to a single plane perpendicular to the longitudinal axis of the element tube.

As shown in Fig. 2, it is further arranged that 75 as the guide pin 105 moves into the latch ring

107 the ports 114 of the tube 73 move into communication with the ports 115 of the cylinder tube 78 which open directly into the fluid chest and the cleaning fluid contained in the fluid chest 80 thus flows into the element tube 73 and is discharged through the apertures 71. As the element tube 73 is retracted ports 114 move away from ports 115 and the supply of cleaning fluid is cut off. Inasmuch as the fluid chest 80 carries the full cleaning fluid pressure any desired 10 reduction of pressure must be determined by the size of ports 114 and 115. A seal disc 116 set in the element tube 73 prevents the cleaning fluid from filling that part of the element tube 73 farthest from the nozzle 70 and piston ring 117 15 prevents the leakage of cleaning fluid between the element tube 73 and the cylinder tube 78 until the rings 117 pass the edge of the ports 115 in fluid chest 80.

It is sometimes desirable or necessary to have 20 a nozzle which will travel longitudinally without rotation until it reaches its blowing position where it may be rotated about the axis of the element tube and then withdrawn without further rotation. An optional form of my invention 25 for accomplishing this end is shown in Figs. 6 and 7.

This embodiment of my invention differs from that above described in the provision of a guide tube 120 having a longitudinal keyway 121. The 30 tube 120 is welded or fixedly secured in any suitable manner to the casing 74 and has an inside diameter capable of receiving the element tube 73 in sliding engagement. A guide pin 106^A fixed to the element tube 73 has a portion 122 extending into the longitudinal keyway 121 and a portion 123 residing between the helical coils of spiral 75^A which is fixedly secured to the drive-shaft 97.

With the element tube 73 in its retracted position rotation of the drive shaft 97 in a counter-clockwise direction results in a similar movement of the spiral 75^A. This movement of the spiral 75^A is imparted through the portion 123 to the pin 106^A. Inasmuch as the extended portion 122 45 in the keyway 121 prevents rotation the pin 106^A and the attached element tube 73 are forced outwardly from the casing 74. At the end of its travel in the keyway 121 the portion 122 passes into the notch 108^A of the latch ring 107^A and 50 continues movement of the drive shaft 97 results in rotation of the nozzle without further longitudinal movement of the element tube 73 or nozzle 72 as previously described. The latching arrangement for effecting withdrawal of the element tube to its inoperative position is identical to that of the first described form excepting for the shape of the pin receiving notch 108^A in the latch ring 107^A. The notch 108^A is formed as an extension of the keyway 121 and may conveniently be U-shaped as shown in Fig. 7.

To cool the element tube 73 when it is standing in its idle position a line 118 from a suitable source of fluid under pressure as, for example, air is tapped into the cylinder tube 78 so as to communicate with the ports 114. Thus there is a constant flow of cooling fluid through that part of the element tube 73 nearest the boiler and through the nozzle when the device is in its inoperative position. As the element tube 73 60 moves into the operating position the ports 114 move away from the line 118 and the cooling fluid is cut off by the walls of the element tube 73. The sliding surfaces of the element tube 73 and the cylinder tube 78 may be lubricated by grease 75

cups 119 provided at convenient points in the cylinder tube 78.

Thus it will be seen that I have provided a boiler cleaner capable of being moved axially from an idle to an operating position and there rotated about its longitudinal axis in an arc of any desired number of degrees, wherein the full cleaning fluid pressure is carried to the element tube and there reduced to the desired blowing pressure by ports in the element tube. I have further provided improved means for placing the boiler cleaner in its blowing position and for subsequently withdrawing it to its rest position, and means for cooling the element tube and nozzle while in the idle position.

15 What I claim as my invention is:

1. In a fluid heater cleaner, a casing housing, a movable blower tube, means for moving said blower element to a predetermined position outwardly of said casing and there rotating said tube about its longitudinal axis through any desired number of rotations, said means comprising co-operating guide members causing longitudinal and rotative movements of said tube under manual actuation, said members disengaging after a predetermined longitudinal travel, a third member freely rotatable in one direction with which one of said guide members engages upon disengagement with the other of said guide members, means restraining said third member against rotation in reverse direction, and means causing disengagement of said third member and the guide member with which it engages and automatic re-engagement of said guide members upon reversal of said manual actuation.

35 2. In a fluid heater cleaner, a casing housing, a movable blower tube, means for moving said blower element to a predetermined position outwardly of said casing and there rotating said tube about its longitudinal axis through any desired number of rotations, said means comprising co-operating guide members causing longitudinal and rotative movements of said tube under manual actuation, one of said guide members comprising a stationary spirally grooved member, the 40 other guide member comprising a rotatable element connected to said tube and having a radial pin extending into the spiral groove in such manner that rotation of the element causes longitudinal movement of the element and tube, said pin being adapted to disengage from said spiral groove after a predetermined longitudinal travel, a third member freely rotatable in one direction with which said pin engages upon disengagement with the spiral groove, means restraining said 45 third member against rotation in reverse direction, and means causing disengagement of said pin and third member and automatic re-engagement of said pin with said spiral groove upon reversal of rotation of said rotatable element.

60 3. In a fluid heater cleaner, a casing housing, a movable blower tube, means for moving said blower element to a predetermined position outwardly of said casing and there rotating said tube about its longitudinal axis through any desired number of rotations, said means comprising co-operating guide members causing longitudinal and rotative movements of said tube under manual actuation, said members disengaging after a predetermined longitudinal travel, a ring freely 65 rotatable in one direction and having means for the reception of one of said guide members upon disengagement of said one guide member with the other guide member, said means including means for causing automatic restoration of said 70 one guide means with the other guide means

upon relative rotation of the guide means and ring in a reverse direction, and means for restraining reverse rotation of said ring whereby the guide means rotates reversely relative thereto upon reverse actuation of said guide means. 5

4. In a fluid heater cleaner, a casing housing, a movable blower tube, means for moving said blower element to a predetermined position outwardly of said casing and there rotating said tube about its longitudinal axis through any desired 10 number of rotations, said means comprising co-operating guide members causing longitudinal and rotative movements of said tube under manual actuation, one of said guide members comprising a stationary spirally grooved member, the 15 other guide member comprising a rotatable element connected to said tube and having a radial pin extending into the spiral groove in such manner that rotation of the element causes longitudinal movement of the element and tube, said 20 pin being adapted to disengage from said spiral groove after a predetermined longitudinal travel, a ring freely rotatable in one direction and having a notch with which said pin engages upon disengagement with the spiral groove, means restraining 25 rotation of said ring in a reverse direction, and said notch having a wall so shaped to cause disengagement of said pin therewith and automatic re-engagement of said pin with said spiral groove upon reversal of rotation of said 30 rotatable element.

5. In combination, a casing having an internal spiral groove, a drive shaft rotatable in said housing, a nut slidably and non-rotatively mounted on said drive shaft and having a pin extending radially therefrom into said groove in such manner that rotation of the shaft causes rotation and longitudinal movement of the nut, an element tube connected to said nut for rotation and longitudinal movement therewith, said element tube 40 having a discharge nozzle and means for supplying cleaning fluid thereto, said pin being adapted to ride from the end and disengage the spiral groove after a predetermined longitudinal travel thereof, a member freely rotatable in one direction with which said pin engages upon disengagement with the spiral groove, means restraining rotation of said member in reverse direction, and means causing disengagement of said member and pin and automatic re-engagement of the pin 45 with the groove upon reversal of rotation of said shaft. 50

6. In combination, a casing having an internal spiral groove, a drive shaft rotatable in said housing, a nut slidably and non-rotatively mounted 55 on said drive shaft and having a pin extending radially therefrom into said groove in such manner that rotation of the shaft causes rotation and longitudinal movement of the nut, an element tube connected to said nut for rotation and longitudinal movement therewith, said element tube having a discharge nozzle and means for supplying cleaning fluid thereto, said pin being adapted to ride from the end and disengage the spiral groove after a predetermined longitudinal travel thereof, a ring freely rotatable in one direction and having means for reception of said pin upon disengagement thereof with said groove, said means including means for causing automatic restoration of said pin with said spiral groove 60 upon relative rotation of the nut and ring in reverse direction, and means for restraining reverse rotation of the ring whereby the nut rotates reversely relative thereto upon reverse rotation of the shaft. 65

7. In combination, a casing having an internal 70

75 spiral groove, a drive shaft rotatable in said housing, a nut slidably and non-rotatively mounted on said drive shaft and having a pin extending radially therefrom into said groove in such manner that rotation of the shaft causes rotation and longitudinal movement of the nut, an element tube connected to said nut for rotation and longitudinal movement therewith, said element tube having a discharge nozzle and means for supplying cleaning fluid thereto, said pin being adapted to ride from the end and disengage the spiral groove after a predetermined longitudinal travel thereof, a ring freely rotatable in one direction and having means for reception of said pin upon disengagement thereof with said groove, said means including means for causing automatic restoration of said pin with said spiral groove upon relative rotation of the nut and ring in reverse direction, and means for restraining reverse rotation of the ring whereby the nut rotates reversely relative thereto upon reverse rotation of the shaft. 75

spiral groove, a drive shaft rotatable in said housing, a nut slidably and non-rotatively mounted on said drive shaft and having a pin extending radially therefrom into said groove in such manner that rotation of the shaft causes rotation and longitudinal movement of the nut, an element tube connected to said nut for rotation and longitudinal movement therewith, said element tube having a discharge nozzle and means for supplying cleaning fluid thereto, said pin being adapted to ride from the end and disengage the spiral

groove after a predetermined longitudinal travel thereof, a ring freely rotatable in one direction and having a notch with which said pin engages upon disengagement with said spiral groove, means for restraining reverse rotation of said ring, and cam-like means for causing disengagement of the pin with the notch and automatic reengagement of the pin with the spiral groove upon reversal of rotation of the shaft relative to the ring. 5

LE ROY S. DE MART. 10
